UNITED STATES PATENT OFFICE.

HENRY SYMONDS, OF LONGBEACH, CALIFORNIA, ASSIGNOR, BY DIRECT AND MESNE ASSIGNMENTS, TO SUPERIOR LIGHT AND HEAT CO., OF LOS ANGELES, CALIFORNIA, A CORPORATION OF CALIFORNIA.

ACETYLENE-GAS GENERATOR.

No. 806,087.

Specification of Letters Patent.

Patented Nov. 28, 1905.

Application filed September 16, 1904. Serial No. 224,745.

To all whom it may concern:

Be it known that I, HENRY SYMONDS, a citizen of the United States, residing in the city of Longbeach, county of Los Angeles, and State 5 of California, have invented new and useful Improvements in Acetylene-Gas Machines, of which the following is a specification.

My invention relates to means to control the feed of carbid in such machines and to other 10 features thereof hereinafter described; and the object thereof is to provide a simple and efficient machine. I accomplish this object by the mechanism described herein and illustrated in the accompanying drawings, in which—

15 Figure 1 is a cross-section taken on line 1 1 of Fig. 2. Fig. 2 is a central vertical section of the generator and gas-holder. Fig. 3 is a side elevation, partly in section, with parts broken away. Fig. 4 is a central vertical section of the carbid-chamber and its outlet-chamber with the carbid-controlling valves in elevation. Fig. 5 is a detail of the top of the valve-operating rod.

20 In the drawings, 6 is the carbid-chamber, which is provided with a port 7 in the bottom thereof, which opens into chamber 8, which I will call a "safety-chamber." This safety-chamber is provided with a port 9 in the bottom thereof, which opens into a hood 10, that 25 opens into the generator-chamber 11, projecting downwardly therewith. On the lower end of the casing of the safety-chamber is a moisture-deflecting collar 12, which prevents any moisture which collects in the top of the hood 30 from running down the outside wall of the safety-chamber to the outlet thereof. The top of the carbid-chamber is provided with a screw-cap 13, which is removed when it is desired to refill the chamber. A brace 14 supports a cap 15 secured thereto, which cap 35 covers the upper end of the carbid-valve-operating rod 16, upon which is slidably mounted a sleeve 17, which carries near its lower end conical-shaped valves 18 and 19, which control port 7 of the carbid-chamber and port 9 of the safety-chamber. Valve 19 will deflect the carbid as it falls from the safety-chamber so it will fall into the water at a point outside of the vertical line projected from the moisture-collar 12, thereby causing the principal 45 part of the steam to arise outside of the collar. Below valve 19 is a supporting-cone 20, which is rigidly secured to the valve-operating

rod 16. This valve-operating rod carries on the top thereof, within cap 15, a nut 21, between which and brace 14 is spring 22, which is adapted normally to hold valve 18 so that it closes port 7 and valve 19 to close port 9. This rod is U-shaped, as best shown in Fig. 2, and passes upwardly and out of the generating-chamber through the guide-tube 23, which is secured in partition 24, which partition forms the top of the generating-chamber. A sealing-tube 25 is secured to rod 16 and is telescopically movable upon tube 23 to prevent any gas escaping upwardly through said tube. The exterior end of rod 16 terminates in a yoke 16', and between this yoke and cover 26 is spiral spring 27, which also normally holds valves 18 and 19 to close ports 7 and 9, 55 respectively. Mounted on the top of gas-bell 28 is a standard 29, which carries an arm 29', which passes through yoke 16' and is adapted to contact therewith and depress the valve-operating rod so as to open valves 18 and 19 when the gas in said bell is nearly exhausted. Should an excess of carbid fall into the generator-chamber by reason of the failure of valves 18 and 19 shutting off the supply of carbid, the accumulation of gas in the bell 60 will cause it to rise until arm 29' contacts with the top of the yoke and will raise said rod to a height sufficient to seat valves 18 and 19 or will prevent the further rise of the gas-bell, at which time ports 30 in sealing-tube 31 will be so close to the water-line 32 in the gas-bell that the gas will pass 65 through said ports 33 in sealing-tube 34, which is telescopically movable upon pipe 35, which pipe opens into the condensing-chamber 36 70 and serves as an escape-pipe for the gas which passes therethrough and into the condensing-chamber and from thence through pipe 37 and through outlet 38, (shown in Fig. 1,) which outlet may be connected by pipe to lead the 75 gas outside the building if the gas-machine is kept within an inclosed building. The generator-chamber is provided with a filling-spout 39, and the water necessary to fill the machine passes therefrom through port 40 and thence through tube 41, having a number of small ports 42 in the vertical wall thereof and near its bottom, as shown in Fig. 2. This tube I will call a "filling-tube," and passing therethrough is rod 43, having handle 44 on 80 the top thereof and stirrer-blade 45 on the

bottom thereof, which stirrer is operated to cause the ash to flow out through pipe 46 when the machine is being cleaned. Leading from the generator-chamber is the supply-pipe 47, which terminates in the gas-bell. On the pipe 47 is a three-way valve 48, which valve is also connected to pipe 37. This valve may be turned so as to connect pipes 48 and 37 to admit air into the generator-chamber 10 when the same is being cleaned and also to permit the escape of air out of the generator-chamber when it is being filled with water, or said valve may be turned to cause the gas to flow into the holder. From the gas-bell a pipe 49 leads the gas to a purifier 50, and pipe 51 leads the gas therefrom to the place of use. The safety-chamber is removably secured to the top of chamber 10 by bolts 54. Hood 10 is provided with a plurality of holes 55, through which the gas that rises in the hood is forced in detached streams, thereby washing the gas better than if it were not separated into jets.

Arm 29' is slidable through its support 29, which support is secured to the gas-bell, so that when it is desired to refill the machine said arm can be removed away from engagement with yoke 16', thereby permitting springs 22 and 27 to bring valves 18 and 19 to close ports 7 and 9, respectively, when the chamber 30 can be refilled.

It will be observed that in case the user neglects to disconnect arm 29' from yoke 16' valve 19 will be in the position shown in Fig. 4, which closes port 9, and that the safety-chamber will fill with carbid and that the valve will not rise so as to open port 9, and the carbid will then have to be removed from the machine and valve 18 permitted to close port 7 before the carbid-chamber is in a proper position to receive a new supply, thus putting an effective check upon the improper filling of the machine, as no carbid can possibly get into the water in the generator until the valves are in their proper position. As soon as the carbid-chamber is refilled and cap 13 replaced the carbid-operating rod is depressed by hand until the gas-bell rises to a point where arm 29' can be slid back with the end thereof projecting through yoke 16'. It will also be observed that as ports 42 are in the vertical wall of the filling-tube and that the tube is in close engagement at the bottom with the stirrer-operating rod no gas will escape therethrough and that said tube performs the functions of a seal around this stirrer-rod and a filling-tube. The condensing-chamber 36 is provided with a filling-spout 52 for filling said chamber with the necessary water, which passes through port 53 into said chamber.

Having described my invention, what I claim as new, and desire to secure by Letters Patent, is—

1. In an acetylene-gas machine the combination of a generating-chamber; a carbid-chamber above said generating-chamber; a

safety-chamber below said carbid-chamber and connected thereto and to the generating-chamber, said safety-chamber having a port in the top thereof communicating with the carbid-chamber and a second port in the bottom thereof communicating with the generating-chamber; a valve in said safety-chamber; and means to move said valve to close the communication between the carbid-chamber and the safety-chamber whenever the gas-pressure in the generating-chamber rises above a predetermined pressure, whereby the flow of carbid is stopped at the top of the safety-chamber. 75

2. In an acetylene-gas machine the combination of a generating-chamber; a carbid-chamber above said generating-chamber and having a port in the bottom thereof; a safety-chamber below said carbid-chamber having a port in the bottom thereof; a collar secured to said safety-chamber on the outside of and near the port in the bottom thereof; a valve adapted to normally control the port in the bottom of the carbid-chamber, and also to control the port in bottom of the safety-chamber; a second valve connected to the first valve, said second valve being adapted normally to close the port in the bottom of the safety-chamber to deflect the carbid from a vertical line as same passes out of the safety-chamber; 95 means to operate said valves.

3. In an acetylene-gas machine the combination of a generating-chamber; a carbid-chamber above said generating-chamber and having a port in the bottom thereof; a safety-chamber below said carbid-chamber having a port in the bottom thereof; a collar surrounding the lower end of said safety-chamber and projecting downwardly thereinto and provided with a plurality of openings near the bottom of said hood, said hood surrounding said safety-chamber; a U-shaped rod having one arm thereof passing through the ports in the carbid and safety chambers and the other arm passing through the top of the generating-chamber; a supporting-cone rigidly secured to the arm of said rod which passes through said safety-chamber; conical-shaped valves slidably mounted on said rod above said cone one of said valves being adapted to close the ports in the carbid and safety chambers; a brace in said chamber through which said rod passes; a nut on the end of said rod above said brace; a spring on said rod intermediate said rod and brace; a yoke on the other end of said rod; a spring on said rod intermediate said yoke and generator; a gas-bell; a support secured thereto; an arm slidably mounted in said support and adapted to be passed into and out of the yoke 125 on the end of the valve-operating rod.

4. In an acetylene-gas machine of the character herein described, a safety-chamber intermediate the carbid-chamber and generating-chamber, having a port in the bottom 130

thereof; a carbid-chamber above said safety-chamber having a port in the bottom thereof opening into said safety-chamber; a valve-rod passing through said ports; valves on said rod, one valve being within said safety-chamber and adapted to control the flow of carbid from the generating-chamber and to close the port in the bottom of the safety-chamber when the carbid is exhausted, the other valve being below the safety-chamber and adapted to close the port in the bottom thereof when the other valve closes the port in the bottom of the carbid-chamber; and means to operate said rod.

5. In an acetylene-gas machine of the character herein described a U-shaped valve-operating rod; valves on said rod; springs on said rod adapted to hold the valves in a closed position; a yoke on the end of said rod; a gas-bell; means carried thereon to enter said yoke and operate with its said valves.

In witness that I claim the foregoing I have hereunto subscribed my name this 8th day of September, 1904.

HENRY SYMONDS.
